UNITED STATES PATENT OFFICE.

WILLIAM F. WITTICH, OF ERIE, PENNSYLVANIA.

ROLLER-BEARING.

1,141,743.

Specification of Letters Patent. Patented June 1, 1915.

Application filed July 3, 1911. Serial No. 636,706.

To all whom it may concern:

Be it known that I, WILLIAM F. WITTICH, a citizen of the United States, residing at Erie, in the county of Erie and State of Pennsylvania, have invented new and useful Improvements in Roller-Bearings, of which the following is a specification.

This invention relates to roller bearings, and consists in certain improvements in the construction thereof as will be hereinafter fully described and pointed out in the claim.

The invention is illustrated in the accompanying drawings as follows:

Figure 1 shows a side elevation of the bearing with a side plate removed to better show construction. Fig. 2 a section on the line 2—2 in Fig. 1.

As shown, the bearing is arranged with rotary cutters in connection with boring or tunneling machines.

1 marks the shaft on which the bearing is mounted, 2 a roller bearing ring next to the shaft, 3 a floating ring, 4 a second roller bearing ring, 5 a tool bearing ring, and 6 tools mounted on the tool bearing ring.

Pins 7 extend through the rings 2, forming bearing pins at each side of the ring 2, the axes of the pins 7 being in an axial direction. Rollers 8 are arranged on these pins at each side of the ring 2. These rollers are of a size to engage the shaft 1 and the walls of the floating ring 3. In some bearings, but one roller bearing ring 2 is required. Where this is the case, the ring 3 would constitute the outer wall of the bearing. On each side of the ring 2 are ears 9. The pins extend through these

ears in a radial direction (see dotted lines) and rollers 10 are arranged on the ends of the pins. These rollers are of a size to extend slightly beyond the floating ring 3, or immediate surfaces so as to take the end thrust of the bearing.

The ring 4 is of similar construction as 45 the ring 2. It is provided with the pins 11 corresponding to the pins 7, rollers 12 corresponding to the rollers 8, ears 13 corresponding to the ears 9, and the pins 13^a similar to the pins extending through the 50 ears 9, and 14 rollers corresponding to the rollers 10 journaled on the pins 13^a.

Side plates 15 are arranged at the sides of the bearing and washer plates 16 are arranged between the different sets of tools 55 as shown in Fig. 2, these being provided with the felt washers 17.

What I claim as new is:

In a roller bearing, the combination of outer and inner walls; a roller carrying ring 60 next to the inner wall; a roller carrying ring next to the outer wall; an interposed floating ring; and rollers mounted on each side of said roller carrying rings with their axes 65 extending in an axial direction relatively to the bearing and engaging said walls and said floating ring, said roller carrying rings having rollers mounted thereon with their axes extending in a radial direction.

In testimony whereof I have hereunto set 70 my hand in the presence of two subscribing witnesses.

WILLIAM F. WITTICH.
